(57) CLAIM

The ornamental design for a phone case with detachable back panel, as shown and described.

DESCRIPTION

FIG. 1 is a front perspective view of the phone case portion of the phone case with detachable back panel, isolated for clarity of illustration;

FIG. 2 is a rear perspective thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a front perspective view of the detachable back panel; isolated for clarity of illustration;

FIG. 10 is a rear perspective view thereof;

FIG. 11 is a front view thereof;

FIG. 12 is a rear view thereof;

FIG. 13 is a left view thereof;

FIG. 14 is a right view thereof;

FIG. 15 is a top view thereof;

FIG. 16 is a bottom view thereof;

FIG. 17 is an exploded perspective view of the phone case with detachable back panel;

FIG. 18 is a front perspective view thereof;

FIG. 19 is a rear perspective view thereof;

FIG. 20 is a front view of the FIG. 18;
 FIG. 21 is a rear view thereof;
 FIG. 22 is a left view thereof;
 FIG. 23 is a right view thereof;
 FIG. 24 is a top view thereof; and,
 FIG. 25 is a bottom view thereof.

The broken lines in the drawings depict portions of the phone case with detachable back panel that form no part of the claimed design.
